(57) **CLAIM**

The ornamental design for an intelligent fitness mirror, as shown and described.

DESCRIPTION

FIG. 1 is a top, right front perspective view of an intelligent fitness mirror showing our new design;

FIG. 2 is a top, left back perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof;

FIG. 8 is a bottom view thereof;

FIG. 9 is a right-side view shown in a collapsed state thereof;

FIG. 10 is a top, right front perspective view of a second embodiment of an intelligent fitness mirror;

FIG. 11 is a top, left back perspective view of the second embodiment thereof;

FIG. 12 is a front view of the second embodiment thereof;

FIG. 13 is a back view of the second embodiment thereof;

FIG. 14 is a left-side view of the second embodiment thereof;

FIG. 15 is a right-side view of the second embodiment thereof;

FIG. 16 is a top view of the second embodiment thereof;

and,

FIG. 17 is a bottom view of the second embodiment thereof.

The broken lines shown in the drawings illustrate structure

or features that form no part of the claimed design.

1 Claim, 15 Drawing Sheets
